WILLIAM A. HALL, OF NEW YORK, N. Y., ASSIGNOR TO MOTOR PETROL COMPANY, OF BRATTLEBORO, VERMONT, A CORPORATION OF VERMONT.

ART OF CONVERTING HYDROCARBON.

1,261,930.

Specification of Letters Patent.

Patented Apr. 9, 1918.

Application filed May 24, 1913. Serial No. 769,610.

To all whom it may concern:

Be it known that I, WILLIAM A. HALL, a citizen of the United States, residing at New York, in the county of New York and State 5 of New York, have invented or discovered certain new and useful Improvements in the Art of Converting Hydrocarbons, of which the following is a specification, reference being had therein to the accompanying drawing.

This invention or discovery relates to the art of converting hydrocarbons for the purpose of obtaining, from a relatively heavy hydrocarbon oil, a lighter (lower specific 15 gravity) and more volatile product. Various attempts, involving several different processes, have heretofore been made in this direction, but, so far as is known to me, these attempts have been only partially successful, and have not been practised largely 20 in a commercial way. I have, however, discovered that a relatively light and volatile hydrocarbon spirit may be readily produced from a relatively heavy hydrocarbon liquid 25 by a simple process, as will hereinafter appear.

The present invention or discovery is carried into effect by withdrawing a certain percentage of the carbon from a heavy hydrocarbon, thereby producing a lighter (lower specific gravity) and more volatile product. This result is secured by passing 30 a mixture of heavy hydrocarbon oil and water (which latter may be in the form of steam) through a highly heated chamber with restricted spacings so that its passage is retarded to an extent sufficient to create a considerable pressure, preferably about 35 150 pounds to the square inch. In thus passing this mixture through the highly heated chamber, as stated, the whole mixture becomes vaporized, and a considerable amount of carbon is deposited on the walls 40 or surfaces which obstruct the passage of the vaporized mixture, so that the residue, when condensed and thereby separated from the fixed gases, will yield a relatively light hydrocarbon liquid product.

While the relative proportions of oil and 45 water may be varied more or less, I find that particularly good results may be secured if

about one pound of water is employed for each two or two and one-half pounds of oil (being weighed as liquids).

The accompanying drawing illustrates 55 somewhat conventionally, in sectional elevation, an apparatus by which the present invention or discovery may be carried into effect.

Referring to the drawing, 12 denotes a 60 receptacle, of any suitable form in cross section, and which is divided, by a screen 13, into receiving and converting chambers 14 and 15, respectively. The receptacle 12 is inclosed by a casing 16 which retains the 65 heat and affords a heating chamber 17 below the said receptacle. In the said heating chamber is located a heating burner 18 to which gas is supplied through a pipe 19. The oil to be converted is discharged under 70 suitable pressure into the receiving chamber 14 through a pipe 20 communicating with a suitable pump, and the water which is to be mixed with the oil is preferably supplied to the said receiving chamber in the form 75 of steam which may be forced into said chamber through a pipe 21. The converting chamber 15 is preferably partly or wholly filled with a suitable metal in small pieces which by being more or less compacted together, will serve to obstruct the flow of the hydrocarbon through the converting chamber, and thus produce back pressure, and these small pieces of metal will afford numerous surfaces on which a 80 portion of the carbon in the vaporized mixture is deposited in solid form. Preferably these particles of metal will be in the form of nickel balls or cubes, as nickel neither 85 oxidizes nor carbonizes at the high temperature (about 600° C.) which is employed, but it will be understood that forms other than balls or cubes may be employed, if 90 desired.

In carrying the invention into effect a 95 series of decarbonizers or converters such as that shown in the accompanying drawing will be so arranged that they can be connected together and the oil will be passed from one to another, as by passing it 100 through a pipe, as 22, communicating with the converting chamber 15 to a chamber cor-

responding to the receiving chamber 14 of another decarbonizer or converter, and thus the mixture may be successively treated to withdraw any desired amount of carbon 5 therefrom and thus secure a product of any desired lightness and volatility.

In thus passing the liquid hydrocarbon through a series of these converters a considerable amount of carbon is deposited in 10 solid form on the surfaces of the fragments or small pieces of metal with which the converting chambers are supplied, and the process may be carried on until the particles of metal in the converting chamber become 15 so clogged with carbon that it will be necessary to throw it out of operation for cleaning, which may be done simply by flooding with steam or water, as the solid carbon is in the form of loose soot. Thus in using 20 a series of these converters the connections may be such that some of them may be cut out, for the purpose of cleaning, while the others may be continued in operation.

The hydrocarbon spirit produced as hereinbefore described, and which is of a lower specific gravity and lower boiling point than the original hydrocarbon liquid before treatment, contains compounds of the ethylene or olefin series, although before treatment the 25 liquid hydrocarbon was composed principally of members of the paraffin series. The lower specific gravity and lower boiling point of the treated hydrocarbon liquid is in my opinion due entirely to its loss of 30 carbon. In other words, the essential feature of the present improved process consists in lightening, lowering of the specific gravity, and also the boiling point of a hydrocarbon liquid by withdrawing a portion of 35 its carbon, in contradistinction to such previous processes as consisted in lightening the hydrocarbon liquid by increasing its percentage of hydrogen, or by causing a 40 chemical reaction to take place between the oil and the elements of water. This converted hydrocarbon spirit is, as will be understood, suitable for use in internal combustion engines, and as it is produced by a relatively simple and easily practised 45 process the cost of the product will be comparatively low.

As to the rate of flow of the vaporized oil and water through the mass of catalytic metal, it is impossible to lay down any hard 50 and fast rule, except that the rate of flow is preferably such as to give a pressure of about 150 lbs. per square inch, at a temperature of 600° C. The oil vapor and steam may be in contact with the nickel for about 55 two to three minutes, giving excellent results.

The mineral oil operated upon may be a crude California oil, of a specific gravity of about .955, although other oils such as crude

Pennsylvania, Ohio, Canadian, Texas oils, 60 or stripped oils may be employed with good results.

After passing through one or more converters of the form illustrated, the vaporous products are led to a condenser, where light 70 oil and water are condensed, and after settling, the two are separated by decantation, in a manner well known in the petroleum industry.

It will be noted that in the above description I have referred to the use of nickel in the chamber 12, with which the steam and oil vapor are brought into contact. It will be noted that nickel used in this connection has a very different effect from that which 75 would be produced if metal were employed, which would be oxidizable under the existing conditions, for example iron. At the temperature stated, iron will decompose steam, in the presence of oil vapor, to produce an oxid of iron, and some free hydrogen will be produced. In such a process however, the pieces of iron would soon become coated with a layer of iron oxid, which would prevent further action of the 80 iron and steam upon each other. With nickel, however, the metal does not become oxidized, in the presence of oil vapor. Iron which has heretofore been suggested in a somewhat similar process, was used as a 85 chemical agent, an agent suitable for the reduction of steam (oxid of hydrogen) to form hydrogen (with the consequent formation of oxid of iron). In my process, however, the nickel does not have any action 90 of this character, but acts as a catalytic agent. I am familiar with the U. S. Patent to Noad, No. 971,468, dated September 27, 1910, and I make no claim to anything 95 shown in said patent.

Having thus described my invention or discovery I claim and desire to secure by Letters Patent:

1. The herein described process of reducing the specific gravity of a hydrocarbon liquid, by the extraction of a portion of its carbon content in solid elemental form, which comprises subjecting the hydrocarbon, in vaporized form, to the simultaneous action of heat and steam, in the presence of a catalytic metal which is non-oxidizable and non-carbonizable in the presence of steam and oil vapor, while at a high temperature, and while under a pressure substantially above atmospheric.

2. The herein described method of producing a relatively light hydrocarbon liquid, which comprises decomposing a relatively heavy hydrocarbon liquid, and extracting in solid elemental form, a portion of its 120 carbon content, by subjecting said relatively heavy hydrocarbon to a temperature approaching a red heat while under a pressure

materially above atmospheric, applied in
the presence of water in the form of steam,
in a chamber containing numerous small
pieces of a catalytic metal which is non-
oxidizable under these conditions, and sub-
sequently condensing the vaporized residue
of hydrocarbon and water.

In testimony whereof I affix my signature,
in presence of two witnesses.

WILLIAM A. HALL
